Primary Examiner — Brett Miller*Assistant Examiner* — Rani J Abdallah(74) *Attorney, Agent, or Firm* — Sorell, Lenna &
Schmidt, LLP(57) **CLAIM**

The ornamental design for a wide mouth container, as shown and described.

DESCRIPTION

FIG. 1 is a perspective view of a wide mouth container;
FIG. 2 is a front view of the wide mouth container;
FIG. 3 is a side view of the wide mouth container;
FIG. 4 is a rear view of the wide mouth container;
FIG. 5 is a side view of the wide mouth container;
FIG. 6 is a top view of the wide mouth container;
FIG. 7 is a bottom view of the wide mouth container;
FIG. 8 is a partial front view of the wide mouth container;
and,

FIG. 9 is an enlarged cross-sectional view of a portion of the wide mouth container at detail 9-9 in FIG. 8.

The dash-dot broken lines depict portions of the wide mouth container that form no part of the claimed design. The dash-dot broken lines depict the boundaries of the claimed design and form no part thereof.

1 Claim, 9 Drawing Sheets(56)
